Houston & Bates.

UNITED STATES PATENT OFFICE.

ROBERT L. SHORT, OF CLEVELAND, OHIO, ASSIGNOR TO THE CLEVELAND TOY AND MANUFACTURING COMPANY, OF CLEVELAND, OHIO, A CORPORATION OF OHIO.

TOY-CARTRIDGE EXPLoder.

SPECIFICATION forming part of Letters Patent No. 708,084, dated September 2, 1902.

Application filed October 1, 1901. Serial No. 77,235. (No model.)

To all whom it may concern:

Be it known that I, ROBERT L. SHORT, a citizen of the United States, residing at Cleveland, in the county of Cuyahoga and State of Ohio, have invented a certain new and useful Improvement in Toy-Cartridge Exploders, of which the following is a full, clear, and exact description, reference being had to the accompanying drawings.

10 The invention relates to an exploding device adapted to be secured at the end of a stick and when brought down on the pavement or ground to explode an encompassed toy cartridge or cap. Such devices, broadly 15 considered, are well known.

The specific objects of this invention are, first, to enable the exploder to conveniently hold the cartridge or cap so that it will not be liable to drop out; second, to enable the charge 20 to be exploded by bringing the exploder against surfaces more yielding than a stone pavement, for example; third, to endow the construction with sufficient strength so that the largest possible load cannot rupture it; 25 fourth, to enable as loud a report as possible to be produced by the explosion, and, fifth, to enable the device to be produced very cheaply.

The invention may be conveniently summarized as consisting of the combinations of 30 parts which I have devised for the above ends, as hereinafter fully explained, and definitely set out in the claims.

The drawings clearly disclose my invention, wherein—

35 Figure 1 is a perspective of the exploder complete. Figs. 2 and 3 are vertical sections thereof on planes at right angles to each other. Fig. 4 is a bottom plan of the under member of the exploder, and Fig. 5 a bottom plan of 40 the upper member.

Referring to the parts by letters, A represents the upper member of the exploder. In the upper end of this is a socket a, in which tightly seats the reduced lower end of the 45 stick or cane C, by which the exploder is carried.

The lower member of the exploder is designated B. It, like the upper member, consists of a truncated cone. The upper member has 50 a recess a', while the lower member has a cor-

responding boss or projection b', adjusted to seat in the recess a'. The cartridge is a flat tablet and is compressed between the flat surfaces of this recess and projection.

The member B is held in place by a bail D, 55 depending in a U shape from the member A, there being recesses a² on opposite sides of the member A, the bases of which recesses present horizontal walls through which the bail passes and on the upper side of which it 60 is riveted, as indicated at d. The bail lies in a groove b in the member B. Occupying a central recess b² in the member B is a spring E, which bears at one end against the base of the recess, the other end against the inner 65 surface of the bail. The operation of this spring therefore is to tend to cause the two members A and B to contact with each other. The coöperating recess and projection a' and b' have their walls conical, so that while there 70 is plenty of play between them when they are separated they come comparatively snugly together at their nearest approach. The recess a' has a horizontal opening a³ to the outside of the member, and through this opening the flat cartridge is inserted, the member B being grasped by the fingers and drawn 75 away against the force of the spring E to allow the insertion. After the cartridge has been placed the spring E holds it snugly, preventing its escape through the orifice a³ be turned downward. Thus the stick or cane can be loaded and carried over the shoulder, for example, without paying any attention to the position of the orifice a³. This point is of 80 importance, as it allows the cane to be carried loaded for any desired time and exploded at any unexpected point, thereby increasing the pleasure of operation. When the cartridge is in place, it is contained in a comparatively 85 small chamber, so that its explosion produces a large amount of noise. The bail D occupies the groove d loosely enough so that the member B may adjust itself to have the upper surface of the boss b' in contact with the 90 cartridge throughout the surface of the latter, though the cartridge may be uneven, and this large amount of contact and the comparatively large surface at the lower end of the member B allows the exploder to operate 95 100.

when it is brought against the ground or a wooden floor, for example, the device not being limited to use on such a hard surface as a stone pavement.

5. The exploder is very strong, as the strain caused by the explosion is simply a tensile strain on the bail D, which the latter is well able to withstand.

10. The device may be very cheaply constructed, consisting in addition to the stick of but four parts and the only operation required to secure these parts together being the riveting of the ends of the bail.

I claim—

15. 1. In a cartridge-exploder, in combination, an upper member having on diametrically opposite sides horizontal walls, a lower member having in its outer face a downwardly-opening diametric groove extending across the 20 bottom and up the sides of said member, a U-shaped bail occupying said groove and having its ends extending through openings in said walls in the upper member and having upset heads, and a spring tending to bring 25 said members together, substantially as described.

2. In a cartridge-exploder, in combination, an upper member having in its upper end a recess for the reception of a stick and in its 30 lower end a recess opening downward and opening sidewise, a lower member having a projection adapted to enter the bottom recess of the upper member, and having in its

outer face a downwardly-opening diametric groove extending across the bottom and up the sides of said member, a U-shaped bail riveted at its ends to said upper member and occupying said groove in the bottom and sides of said lower member, and a spring tending to bring said members together, substantially as described. 35

3. In a cartridge-exploder, an upper member A formed in conical shape and having a recess in its upper end for the reception of a stick and a flaring recess a' in its lower end, 40 which latter recess also has a lateral opening a², there being a pair of recesses a² a² on opposite sides of the member, combined with a coöperating member B having on its upper surface a conical projection adapted to enter 45 the recess a', said member B having a diametrical groove b, a bail D depending from the member A by having its ends projecting through the member into the recesses a² and there riveted, said bail occupying the groove 50 b, and a spring occupying a central downwardly-opening recess in the member B and bearing against the inner surface of the bail, substantially as described.

In testimony whereof I hereunto affix my 55 signature in the presence of two witnesses.

ROBERT L. SHORT.
